UNITED STATES PATENT OFFICE.

PETER N. LANDINE, OF MILFORD, CONNECTICUT, ASSIGNOR TO THE ROSTAND MANUFACTURING COMPANY, OF MILFORD, CONNECTICUT, A CORPORATION OF CONNECTICUT.

HINGE-JOINT FOR WIND-SHIELDS.

1,161,231.

Specification of Letters Patent. Patented Nov. 23, 1915.

Application filed September 12, 1913, Serial No. 789,435. Renewed September 22, 1915. Serial No. 52,104.

To all whom it may concern:

Be it known that I, PETER N. LANDINE, a citizen of the United States, residing at Milford, New Haven county, State of Connecticut, 5 cut, have invented certain new and useful Improvements in Hinge-Joints for Wind-Shields, of which the following is a full, clear, and exact description.

My invention relates to an improved hinge 10 joint for adjustable wind shields and the like, the object of the present invention being to produce an exceedingly simple, durable and effective construction.

In the drawings, Figure 1 is a side elevation of one corner of a wind shield constructed to embody my invention. Fig. 2 is a section on the line 2—2 of Fig. 1. Figs. 3, 15 4 and 5 are detail views.

1 represents one corner of the frame of 20 the transparent section of the wind shield.

2 represents a supporting arm.

The parts 1 and 2 are adjustably hinged together.

3 is a pivot block of unique construction 25 having a split hub forming an expansible plug and comprising two parts 4—4^a revolvably mounted within a head 5 on the support 2. The hub or plug parts 4—4^a are preferably an integral part of the block 3 30 and are separated by an undercut transverse channel or slot in which is located a wedge 6.

7 is a thumb bolt which screws into the wedge 6, said thumb bolt having a shouldered portion 7^a which rests against the 35 outer side wall of the head 5 so that as the thumb bolt is tightened up, it will draw the wedge 6 outwardly, tending to expand the members 4—4^a, forcing them into binding engagement with the surrounding wall of 40 the head 5, thus locking the frame 1 at any desired angle relatively to the support 2.

In the preferred construction, the block 3 is provided with a shouldered offset 8, and the periphery of the shouldered offset is 45 provided with an annular groove 9 which is covered by a flanged portion 10 of the head 5. A retaining pin or screw 11 carried by the flange 10 may project into the groove 9 to hold the parts against accidental separation 50 in the event the thumb bolt 7 is entirely removed.

By this exceedingly simple form of con-

struction, which is capable of being manufactured at a comparatively small cost, an effective wind shield joint may be produced 55 which possesses the maximum durability.

It will be observed that not only does the action of the thumb screw and wedge tend to expand the two parts of the hub block, but they also draw the hub block laterally 60 into endwise binding engagement with the head so that the entire area of contact between two adjustable parts serves to frictionally hold said parts against accidental displacement.

What I claim is:

1. An adjustable hinge joint for wind shields comprising two relatively movable parts, one of said parts comprising a head having a cylindrical cavity in one face 70 thereof, the other of said parts comprising a hub member including a clamping block transversely slotted and undercut and arranged to seat within the head cavity and to engage the inclosing walls of said head, 75 a clamping member seated in the transversely extending undercut slot in said clamping block between the transversely separated portions thereof and thereby held against rotation in said block, and an operating member carried by the end wall of the head and connected with the clamping member to draw the same laterally toward said end wall, whereby to bring the transversely separated portions of the clamping 80 block into frictional clamping engagement with the walls of the head cavity. 85

2. An adjustable hinge joint for wind shields comprising two relatively movable parts, one of said parts comprising a head 90 having a cylindrical cavity in one face thereof, the other of said parts comprising a hub member including a clamping block, said block being transversely slotted and having its slotted edges undercut, said block 95 being arranged to seat within said head cavity and to engage the adjacent walls of said head, a wedge arranged between the two undercut sections of said block and formed to engage with the undercut edges 100 thereof, an operating device passing through the end wall of said head and screwing into said wedge and having a bearing against said head whereby said wedge may be oper-

- ated to expand said block into frictional clamping engagement with the walls of said head cavity, and means independent of said operating device for holding said relatively 5 movable parts against accidental separation.
3. An adjustable hinge joint for wind shields embodying two relatively movable parts, one of said parts comprising a head having a cylindrical cavity in one side 10 thereof, the other of said parts comprising a hub member, a block carried thereby, said block being transversely divided and undercut and arranged to seat within said head cavity, and engage the adjacent walls thereof, a wedge arranged between the two undercut sections of the hub block, an operating device passing through the end wall of the head and screwing into said wedge, and means for holding the parts against accidental separation independent of the thumb screw, said means 15 comprising a groove in the periphery of the interior part and a projection on the exterior part extending into said groove.
- 20 4. An adjustable hinge joint for wind shields and the like comprising a head having a cylindrical cavity in one side thereof, a frame, a hub block carried thereby, said hub block being transversely divided and undercut and arranged to take a bearing in said head, a wedge arranged between the two undercut sections of the hub block, an operating device passing through the end wall of the head and screwing into said wedge block, and means for holding the 25
- 25 30 35 40 45 50 55 60 65 70 75 80 85 90 95 100

parts against accidental separation independent of the thumb screw.

5. An adjustable hinge joint for wind shields and the like comprising a head having a cylindrical cavity in one side thereof, a frame, a hub block carried thereby, said hub block being transversely divided and undercut and arranged to take a bearing in said head, a wedge arranged between the two undercut sections of the hub block, an operating device passing through the end wall of the head and screwing into said wedge block, and means for holding the parts against accidental separation independent of the thumb screw, said means comprising a groove in the periphery of the interior part and a projection on the exterior part extending into said groove.

6. An adjustable hinge joint for wind shields and the like comprising a head having a cylindrical cavity in one side thereof, a frame, a hub block carried thereby, said hub block being transversely divided and undercut to form two integrally connected hub bearing pieces arranged to take a bearing in said head, a wedge arranged between the two undercut sections of said hub block, an operating device for moving said wedge against said undercut sections to expand the same and force them into combining contact with said head.

PETER N. LANDINE.
